UNITED STATES PATENT OFFICE.

GEORGE W. HENRY, JR., OF PHILADELPHIA, PENNSYLVANIA, ASSIGNOR TO SOABAR COMPANY, OF PHILADELPHIA, PENNSYLVANIA, A CORPORATION OF PENNSYLVANIA.

STOPPING AND STARTING MECHANISM FOR TICKETING MACHINES.

Original application filed December 15, 1923, Serial No. 680,885. Divided and this application filed January 26, 1926. Serial No. 83,865.

My invention relates to certain improvements in ticketing machines, for which Letters Patent were granted to me on the 17th day of October, 1922, No. 1,432,554.

5 The object of the present invention is to improve the construction of the starting and stopping mechanisms of the machine.

In the accompanying drawings:

Fig. 1 is a side view of my improved ticketing machine;

Fig. 2 is a rear end view of the same; and
Fig. 3 is a front end view.

The present application is a division of an application filed by me on December 15, 1923, 15 Serial No. 680,885, for improvements in ticketing machines, which resulted in Patent No. 1,574,391, dated February 23, 1926.

1 is the base of the machine. 2 is an electric motor mounted on the base. 3 is the main 20 frame of the machine, which is also mounted on the base 1. 4 is a longitudinal cam shaft, which is mounted on the frame 3. 5 is a transverse shaft which is connected to the motor shaft 2^a by a coupling 5^a. On the shaft 5 is 25 a worm 6, which meshes with a worm-wheel 7 mounted loosely on the cam shaft 4. On the cam shaft is a cam 8, which actuates a slide 45. 9 is a cam which actuates the printing mechanism 50. 10 is a cam which actuates the shears 57 and the tension mechanism at the 30 head of the machine. The cam shaft 4 extends into the head 11 of the machine and actuates the needle 13 and presser-bar 12.

A longitudinal shaft 25 is mounted in bearings on the underside of the base. On the rear end of the shaft is a pinion 26, which meshes with the teeth of a rack 27, arranged to slide in the bearing 28. The rack is connected to the pivot 29 on an arm of a disk 30. 35 On the forward end of the shaft 25 is a gear-wheel 24, which meshes with a pinion 23. This pinion is mounted on a stud 21^a, on which is a gear-wheel 21 having a pin 87 which is engaged by a latch. This mechanism actuates the looper mechanism and the feed-bar of 40 the machine.

Details of the stitch-forming mechanism are fully set forth in the above-mentioned Patent No. 1,574,391, dated February 23, 45 80 1926.

The pinion 26 is loose on the shaft 25 and has a disk 26^a secured thereto. On this disk

is a pawl 113, which has a spring 114. This pawl engages a notched disk 115, which is secured to the shaft 25. By this construction, 55 the shaft 25 is intermittently turned in one direction only.

On the disk 30 is a pawl 31, which is pivoted at 32. Attached to the pawl is a spring 33. The other end of the spring is secured to 60 the disk 30. On the pawl 31 is a heel 31^a, which is arranged to come in contact with a stop 34, pivoted at 35 to the frame of the machine, and held in normal position by a spring 35^a. The pawl 31 is arranged to engage the 65 teeth of a ratchet-wheel 36 on the worm-wheel 7.

The stop 34 is moved into and out of position by a rod 37, which extends through the length of the machine and is attached to an 70 operating-lever 38 at the front of the machine. This lever is pivoted to the frame at 39 and has a push-pad 40. A spring 41 is connected to the rod 37 and to the frame 3 and tends to hold the rod 37 and the stop 34 in the 75 position shown in Fig. 1, the stop being in engagement with the pawl 31.

When the lever 38 is pushed, the rod 37 is moved in the direction of the arrow, Fig. 1, and turns the stop 34 on its pivot clear of the 80 pawl 31, allowing the pawl to engage the ratchet-wheel 36, giving motion to the parts of the machine.

When the disk 30 makes a revolution, the heel 31^a of the pawl comes in contact with the stop 34, which returns to its normal position 85 as soon as the operator releases the push-lever. This stops the mechanism of the machine, which cannot start again until the operator pushes the lever.

The cam 8 on the shaft 4 has a scroll slot in which extends a pin 42 on a lever 43 pivoted to the frame at 44. The lever 43 is connected to the slide 45 by a link 46. The slide is reciprocated by the cam 8 over the bed 47 on 90 which the strip of tags is fed.

On the lever 43 is an arm 51, which extends under the bar 37, and on the bar 37 is a cam 37^a, under which the arm 51 travels as the slide moves forward. The arm 51 lifts the 100 bar 37 out of engagement with the stop 34, and allows the stop to return to its normal position in the path of the pawl, should the operator fail to release the lever in time.

Pivoted to a stud 80 on the back of the head 11 is an arm 81, having a roller 82 that extends into a groove of a cam 83 which forms an integral part of the cam 10 in the present instance.

Connected to the outer end of the arm 81 is a rod 84 that extends to a latch 85, which is pivoted at 86 to a projection on the base 1. This latch engages a pin 87 on the gear wheel 21 and stops its rotation at a given point. The cam 83 controls the movement of the latch so as to release the gear-wheel at the proper time.

I claim:

1. The combination of a driving shaft; a worm thereon; a cam shaft; a worm wheel loose thereon; a ratchet wheel on the worm wheel; a disk on the cam shaft; a pawl pivotally mounted on the disk; a longitudinal shaft; a pinion loose on the shaft; a pawl connecting the pinion with the shaft; a bearing on the shaft; and a rack bar, pivoted to the disk on the cam shaft, arranged to slide in the bearing, said bar having teeth meshing with the teeth of the gear wheel loose on the longitudinal shaft.

2. The combination in a ticketing machine,

of a frame; a cam shaft; operating means for said shaft; a pivoted stop arranged to control the movement of the operating means; a longitudinally movable bar for moving the stop; an operating lever for the bar, said bar having a cam; a rotary cam on the cam shaft; a lever pivoted to the frame and actuated by the rotary cam; and a slide connected to the lever, said lever having an arm extending under the bar to elevate the bar on the movement of the lever to free the stop.

3. The combination of a driving shaft; a worm thereon; a cam shaft; a worm wheel loose thereon; a ratchet wheel on the worm wheel; a disk on the cam shaft; a pawl pivotally mounted on the disk; a longitudinal shaft; a pinion loose on the shaft; a pawl connecting the pinion with the shaft; a bearing on the shaft; a rack bar, pivoted to the disk on the cam shaft, arranged to slide in the bearing, said bar having teeth meshing with the teeth of the gear wheel loose on the longitudinal shaft; and release mechanism at the opposite end of the longitudinal shaft arranged to stop the rotation of the shaft at a given point.

GEORGE W. HENRY, JR.
